UNITED STATES PATENT OFFICE.

ARTHUR BENJAMIN CRUICKSHANK, OF LONDON, ENGLAND, ASSIGNOR TO HIMSELF, AND JOHN FRACE, OF SAN FRANCISCO, CALIFORNIA.

DESIGN FOR A SYRINGE-BULB.

SPECIFICATION forming part of Design No. 29,409, dated September 27, 1898.

Application filed August 30, 1898. Serial No. 689,875. Term of patent 14 years.

To all whom it may concern.

Be it known that I, ARTHUR BENJAMIN CRUICKSHANK, a subject of the Queen of Great Britain, residing at London, England, 5 have invented and produced a new and original Design for a Syringe-Bulb, of which the following is a specification.

In the drawings, Figure 1 is an elevation. Fig. 2 is a cross-section at the line 2 2, and 10 Fig. 3 is a section at the line 1 1.

The leading feature of this design for a syringe-bulb consists in the design of the elliptical bulb sectionally with a rounded end and tapering at the other end to a neck and 15 cylindrical opening.

The bulb A is elliptical at the section-line 2 2, and one end is rounding at 3, and the bulb tapers at 4 to the neck 5 and cylindrical open end 6.

I claim—

The design for a syringe-bulb, substantially as described and shown.

Signed by me this 5th day of August, 1898.

ARTHUR BENJAMIN CRUICKSHANK.
